DISTILLING APPARATUS

Banks O. Daubert, Hartleton, Pa.

Application October 28, 1933, Serial No. 695,684

1 Claim. (Cl. 202—113)

This invention relates to distilling apparatus and has relation more particularly to an apparatus of this kind especially designed and adapted for use in the dry distillation of shale, coal, lignite, and other like carbonaceous materials to recover oil and gas from such material and in connection with lignite to produce a char which can be used as a fuel to the same advantage as a high grade fuel.

10. It is an object of the invention to provide an apparatus of this kind comprising a series of retorts into which the material to be treated is successively delivered to assure a continuous operation of the apparatus and wherein the retorts are of different temperatures to assure such breaking down material as to effect the desired driving off of the gases.

Another object of the invention is to provide an apparatus of this kind comprising a series of independent retorts successively communicating one with the other together with a delivery mechanism and discharge mechanism for the retorts of a character to assure said retorts at all times being airtight.

25. The invention also has for an object to provide an apparatus of this kind wherein the material to be treated travels through heating zones of different temperatures to break down the material to release the gases therefrom, together with the provision of means whereby such gases before being collected are caused to flow back through the various heating zones to further aid in the breaking down of the material and to drive off the lighter gases.

30. The invention consists in the details of construction and in the combination and arrangement of the several parts of my improved distilling apparatus whereby certain important advantages are attained and the device rendered 40 simpler, less expensive and otherwise more convenient and advantageous for use, as will be hereinafter more fully set forth.

The novel features of my invention will hereinafter be definitely claimed.

45. In order that my invention may be the better understood, I will now proceed to describe the same with reference to the accompanying drawings, wherein:—

50. Figure 1 is a view in top plan and of somewhat a diagrammatic character of a distilling apparatus constructed in accordance with an embodiment of my invention;

55. Figure 2 is a view partly in side elevation and partly in longitudinal vertical section taken through the structure as illustrated in Figure 1,

said figure being on a reduced scale with respect to Figure 1 and also illustrating an associated condenser;

Figure 3 is a fragmentary detail view illustrating the valve mechanism at the delivery end 5 of the apparatus;

Figure 4 is a vertical transverse sectional view taken substantially on the line 4—4 of Figure 3.

As disclosed in the accompanying drawings, my improved apparatus comprises a series of vertically disposed heating chambers 1 formed by the walls 2 of masonry. These chambers 1 are each independent of the other and separated by interposed masonry walls and arranged along and within the lower portion of each of the 15 chambers 1 are the burners 3 in which is used any desired fuel capable of producing the desired results. To one side of the apparatus is a vertically disposed stack 4 closed at the top and having its lower end opening in a conventional manner into an underground draft pit. This stack 4 at points intermediate its ends has in communication therewith the flue pipes 5 leading from the chambers 1 whereby the products of combustion are taken from the chambers 1. 20

Disposed through each of the chambers 1 are a number of retorts 6 positioned above the burners 3 within the chamber and so positioned one with respect to the other and to the walls of the 30 chamber to assure effective circulation of heat around the retorts to produce the desired temperature therein. The number of retorts 6 in a chamber 1 may be as desired and each retort 6 in a chamber 1 is in communication at one end 35 with a corresponding end of the retort in the chamber immediately therebelow by the vertically disposed connecting pipe 7. The pipes 7 connecting adjacent vertical retorts 6 are alternately arranged at opposite ends of the retorts 40 whereby a continuous flow of material may be had therethrough in what may be termed a tortuous path.

Each of the retorts 6 is tightly closed at its ends and the uppermost retort 6 at its extremity remote from its discharge line 7 has in communication therewith from above a feed line 8 extending through the top wall of the masonry and leading from a hopper 9 in which the carbonaceous material, such as lignite, is initially deposited. Interposed in this line 8 is a valve casing 10 in which is snugly engaged for rotary movement a feed valve 11. This valve 11 at diametrically opposed points is provided with the pockets 12 whereby upon rotation of the valve 55

member 11 material from the hopper 9 will be intermittently delivered to the uppermost retort 6, and it is to be particularly noted that the construction and assembly of the valve member 11 within the casing 10 is such as to maintain the line 8 airtight at all times. The valve member 11 is to be rotated in any manner preferred and as the means for operating such valve member forms no particular part of the present invention it is not believed that a description and illustration is required in connection with such operation.

The lowermost retort 6 at one end portion has leading therefrom a discharge pipe line 14 which 15 delivers material to a cylindrical conveyor housing 15 underlying and common to all of the retorts 6 within the lowermost chamber 1. This conveyor housing has its ends closed against admission of air.

20 This housing 15 extends, as disclosed in the accompanying drawings, a desired distance to one side of the masonry structure and said extended portion has a depending discharge spout 16 which delivers within an end portion of an elongated 25 cylindrical cooling chamber 17. This chamber 17 is constructed with spaced walls between which a cooling medium is adapted to be circulated. The end portion of the cooling chamber 17 remote from its communication with the spout 16 30 has in communication therewith a depending discharge spout 18 which intermittently delivers upon a suitably operated carry-off conveyor 19. This discharge spout 18 has interposed therein a suitably operated valve member similar to the 35 valve member 11 hereinbefore referred to whereby by the intermittent discharge from the chamber 17 is effected and at the same time the discharge end of said chamber 17 is maintained at all times closed against the admission of air.

40 Each of the retorts 6 at its upper part is upwardly offset from substantially one end to the other, as at 20, the lower or open face of said offset portion being relatively broad whereby is provided a passage 21 to be hereinafter more 45 particularly referred to.

The open face of the offset portion 20 of a retort 6 also relieves against frictional resistance the upper portion of the spiral blade 22 arranged within each of the retorts 6 and which rotates 50 with the shaft 23. This shaft 23 together with its blade 22 provides a conveyor whereby the material received within one end portion of the retort is carried to the opposite or discharge end of the retort at a desired rate of travel.

55 The shaft 23 may be driven in any desired manner as indicated by the sprocket chains 24 in the accompanying drawings. Any one of the shafts 23 may be directly connected with the desired source of power.

60 It is also to be noted that the feed line 8 communicates with an end portion of an upper retort 6 through the offset portion 20 thereof while each of the discharge pipes 7 is in communication with the offset portion 20 of the retort 6 therebelow.

65 Working in the housing 15 is a suitably driven spiral conveyor 25 and a suitably driven spiral conveyor 26 operates within the cooling chamber 17.

70 Each of the retorts 6 in the uppermost chamber 1 has in communication from above with the offset portion 20 thereof adjacent to the discharge end of such retort a gas carry-off pipe 27 which leads to and discharges within a separating chamber 28. The pipe or line 27 extends within said chamber 28 and terminates at a point relatively

close to the bottom of such chamber. The gas separated in the chamber 28 passes through the line 29 to a condenser 30 of any desired type and leading from the condenser 30 is a gas outlet line 31 which leads to a suitable place of storage 5 for the gas. Interposed in this line 31 is a suitably operated suction fan, generally indicated at 32 in Figure 2, which operates to assure the desired flow of the gas throughout the entire apparatus as will be hereinafter referred to. The line 29 10 adjacent its communication with the condenser 30 has interposed therein a separating trap 33 to assure the gas as it enters the condenser to be substantially pure.

The material, such as lignite, to be treated is 15 initially delivered to the hopper 9 and from said hopper it is intermittently discharged into an uppermost retort 6. This upper retort is heated to between 700° F. and 800° F. and the remaining retorts therebelow in succession are of increased temperature. The second retort from the top is preferably of a temperature of approximately 850° F.; the third retort 950° F.; and the fourth retort 1080° F. It is to be understood that each retort constitutes a heating zone of the 25 same temperature throughout. The material to be treated passes down to the lower retort 6 through the line 1 and the material is moved at desired speed through the retorts under the action of the spiral conveyors 22. As the material passes through the various retorts 6 the material is broken down to allow the release of the gases and as such gases are released they are drawn back through the lower retorts and out through the line 7 and through the line 29 to the condenser 30. This travel of gas is assured by the action of the fan 32 and such travel is further facilitated and assured by the passages 21 provided along the upper portions of the retorts 6. Moisture and other impurities in the gas will be 40 separated as the gas passes through the chamber 28, such separated impurities being carried off through the line 34. The trap 33 hereinbefore referred to and which is in the line 29, also provides for a further separation of the impurities 45 in the gas before the gas enters the condenser, said separated impurities being carried off through the line 35.

In the treatment of lignite, as the same is discharged through the spout 16 into the cooling chamber 17 such material as a result of the release of the gas therefrom is in the best possible condition for use as a fuel. As the material or char is discharged into the chamber 17 the same 50 is immediately subjected to a cooling action which is highly important as the further breaking of the material at that time is no longer desired.

55 By my apparatus as herein disclosed it is believed to be understood that the distillation of the carbonaceous material results in a reduction of moisture and of volatile matter together with the recovery of oils as is particularly facilitated by the separating chamber 28 and trap 33. It is also to be understood from the foregoing that the desired distillation is assured in view of the fact that at all times the retorts 6 are airtight and that the operation is continuous. Furthermore, it is to be noted that each of the retorts 6 of a series 60 are entirely independent of each other so as to assure the maintenance of the desired different temperatures.

65 From the foregoing description it is thought to be obvious that a distilling apparatus constructed in accordance with my invention is particularly 70 75

well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

5 I claim:—

10 An apparatus for carbonizing lignite including a vertical series of horizontally disposed closed metallic retorts, a chamber enclosing each retort, the several chambers being entirely separated from each other each retort having an inlet and an outlet at opposite ends, the outlet of all retorts except the last leading into the inlet of the

15 retort below, open flame heating means individual to and disposed within the several chambers and entirely exterior to each retort, the heating means for each chamber being independently controllable from the heating means for any other chamber, continuously operable means in each retort for causing the material to travel from the inlet of the retort to the outlet end thereof, means for delivering material into the inlet end of the uppermost retort and including means for preventing access of air to the interior of the uppermost retort, means for causing the discharge of material from the lowermost retort including means preventing the inlet of air, means for permitting the gases to pass upward successively from the lowest retort through the successive retorts of the series, and means for positively withdrawing said gases from the uppermost retort.
